MULTIPISTON MOTOR OR PUMP.

Ernst F. Engstrom, Chicago, Ill.

Application December 9, 1947, Serial No. 790,625

19 Claims. (Cl. 103--173)

1

The present invention relates to improvements in hydraulic motors or pumps and more particularly concerns a multi-piston device of this character.

An important object of the present invention is to provide an improved compact, low cost, highly efficient, hydraulic motor or pump adapted to be made in small size.

Another object of the invention is to provide a multi-piston hydraulic motor or pump of high conversion efficiency, that is, such a device in which the power loss ratio due to frictional resistance or back pressures are reduced to practical minimum, and in which an unusually high rate of work or power output in relation to the power input is attained.

A further object of the invention is to provide a novel overlapping thrust multi-piston motor or pump unit.

Still another object of the invention is to provide novel means for effecting distribution of hydraulic pressure fluid in a multi-piston hydraulic motor or pump.

Yet another object of the invention is to provide in a multi-piston hydraulic motor or pump a novel leak-by pressure relieving or scavenging system.

A still further object of the invention is to provide an improved hydraulic multi-piston reversible motor or pump.

It is also an object of the invention to provide an improved method of making a hydraulic fluid distributor for a multi-piston hydraulic motor or pump.

Other objects, features and advantages of the present invention will be readily apparent from the following detailed description of a preferred embodiment thereof, taken in conjunction with the accompanying three sheets of drawings, in which:

Figure 1 is a side elevational view of a hydraulic motor or pump unit embodying the features of the invention;

Figure 2 is a rear end elevational view of the unit of Figure 1;

Figure 3 is a front end elevational view of the unit;

Figure 4 is an enlarged longitudinal sectional view through the unit on the line IV--IV of Figure 3;

Figure 5 is a transverse sectional view through the unit taken substantially on the line V--V of Figure 4;

Figure 6 is a transverse sectional view taken substantially on the line VI--VI of Figure 4;

2

Figure 7 is a transverse sectional view taken substantially on the line VII--VII of Figure 4;

Figure 8 is a fragmentary transverse sectional view taken substantially on the line VIII--VIII of Figure 4;

Figure 9 is a fragmentary transverse sectional view taken in the plane of line IX--IX of Figure 4;

Figure 10 is a longitudinal elevational view, partially in section, of the central shaft and fluid distributor structure of the unit;

Figure 11 is a rear end view of the shaft and distributor structure of Figure 10;

Figure 12 is a front end view of the shaft and distributor structure;

Figure 13 is an enlarged side elevational view of the cam groove ring element of the unit; and

Figure 14 is a fragmentary sectional view taken in the plane of line XIV--XIV of Figure 13.

By the present invention a hydraulic motor or pump is provided having a minimum number of operating parts which are of relatively simple, easily fabricated character, affording unusual compactness in assembly, and efficiency, ruggedness and durability in operation. The construction and operational characteristics are such, moreover, that exceptionally smooth and uniform functional and high loading characteristics are attained for this type of unit.

When operating as a motor, hydraulic fluid under high pressure is supplied to the unit and is translated thereby into rotary power. Facilities are provided for operating the unit with equal efficiency in reverse, and reversal may be effected as nearly as practicable instantaneously. Where the unit is utilized as a pump, rotary power input is translated into hydraulic fluid pressure. No alteration whatsoever is required for using the unit either as a motor or a pump, the only

alternative being whether hydraulic fluid is to be supplied to the unit for activating the same or whether the unit is to create hydraulic fluid pressure. In either use of the unit actuation thereof is smooth, uniform and powerful, there being complete freedom from impulse lags or drags.

In the unit shown in the drawing, a rotary shaft 15 is mounted concentrically within a housing or casing 17, a plurality of reciprocable pistons 18 operable on axes parallel to and in concentric series about the shaft 15 being arranged to drive the same where the unit is operating as a motor, or to be motivated through the medium of the shaft where the unit is operating as a pump. Provision is made for connecting the unit

in a hydraulic fluid circuit through a pair of similar, independent ports 19 and 20 which open through the casing 17 (Figures 1 and 4). One end of the shaft 15, which will herein be referred to as the front end, has an extension 21 which projects beyond the front end of the casing 17 and is adapted to have secured thereto through use of a longitudinal keyway 22, means such as a pulley or gear (not shown) for connecting the same with associated apparatus.

Within the housing 17, the shaft 15 is supported rotatably by front and rear antifriction bearing assemblies 23 and 24, respectively. In the present instance, these are ball bearing assemblies. The forward bearing assembly 23 is preferably larger than the rear bearing assembly 24 and is capable of longitudinal loads, thus serving also as a thrust bearing.

Each of the pistons 18 is preferably identical with each of the others and there may be as many of the pistons 18 spaced in concentric series about the shaft 15 as preferred. In the present instance, the unit has ten of the pistons 18 (Figure 7) which are double acting and have opposite blunt ends affording compression heads each of which is adapted to receive or impart a thrust. As best seen in Figure 4, each of the pistons 18 is of uniform cylindrical shape throughout its major extent and is formed with a narrow medial annular, radially extending thrust rib or shoulder formation 25 of substantially larger diameter than the opposite body portions of the piston. The opposite faces of the annular thrust shoulder formation 25 are finished to a preferred equal taper. In practice a 30° taper has been found highly desirable.

At their forward ends the pistons are slidably guided in respective closely fitting bearing bores or cylinders 27 which open rearwardly into coaxial thrust shoulder clearing bores 28 and at their forward ends into enlarged pressure chamber or cylinder head bores 29. The rear end portions of the piston 18 are closely slidably bearing in coaxial cylinder bores 30 which extend from the thrust shoulder clearance bores 28 and open into enlarged rear end pressure chamber cylinder head bores 31. The lengths of the bearing bores 27 and 30 are so proportioned to the lengths of the respective opposite cylindrical portions of the pistons 18 and are spaced such an axial distance apart that in each reciprocable cycle of the associated piston 18 the compression head terminals of the piston will move between extreme limits into the pressure chambers 29 and 31.

The lengths of the piston strokes in each direction are determined by a thrust transmission member 32 on the shaft 15 cooperating with the thrust shoulder formations 25 of the pistons. As best seen in Figures 4 and 13, the transmission member 32 is in the form of a sleeve or ring provided with a transmission cam groove 33 which is preferably of complementary cross-sectional shape to the tapering shape of the annular piston thrust shoulder formations 25 so that there is a close bearing relationship therebetween and especially between the opposing tapering thrust surfaces thereof. This is accomplished by generating the groove 33 with a cutter of the same profile as the shoulder formation 25 and held, while cutting, in the same relative position as one of the pistons 18 with its thrust shoulder 25. Looseness, lag or slap in operation are thus avoided.

The transmission groove 33 is of generally spiral form and where, as in the present instance,

it is desired to have each of the pistons 18 make two complete reciprocal thrust cycles in each revolution of the shaft 15, the groove comprises equal sections extending 90° about the cam ring in respective reverse directions and with uniform pitch. Thus, in each revolution of the shaft 15, each of the pistons 18 must travel reciprocably to its full opposite reciprocal limits twice, and since the pistons are double acting the ten pistons will be responsible for forty thrusts for each shaft revolution. Furthermore, since the piston thrust ribs or shoulders 25 and the groove 33 are in relatively close bearing relation, the pistons will rotate as the thrust shoulders 25 thereof follow the groove, thereby minimizing wear due to friction.

Hydraulic fluid communication between the ports 19 and 20 and the pistons 18 is effected through a distributing system including structure which herein comprises part of the shaft 15. To this end the shaft is provided between a reduced rear end bearing pilot terminal portion 34 and a front end integral bearing collar 35 with a cylindrical distributor portion 37 of substantial length which is of slightly smaller diameter than the bearing collar portion 35 but of substantially greater diameter than the rear end bearing pilot terminal 34. Formed equidistantly spaced in the portion 37 (Figures 1, 5 and 10) are four coextensive, parallel, identical, generally longitudinally extending fluid distribution channels or grooves 38, 39, 40 and 41. The grooves are of substantial width and preferably have flaring side walls so that they are of the greatest width at the periphery of the shaft portion 37 with, however, substantial land areas between adjacent grooves. The rear portions of the grooves are in straight parallelism. Approximately midway their lengths, the grooves are equally angled to assume respective spiral form in their forward portions to extend 90° around the shaft portion 37.

Completely encircling and enclosing the grooved intermediate distributor portion 37 of the shaft is a coextensive distributor sleeve 42 which is secured to the shaft portion 37 in fluid tight relation and forms a closure for the respective grooves. As best seen in Figures 4 and 5, the sleeve 42 is formed adjacent its rear end, and thus the rear ends of the distributor grooves, with diametrically opposite transverse slots 43 and 44 which register with two of the grooves, for example, the grooves 39 and 41, respectively. The ends of the slots are formed with an even greater angular flare than the walls of the grooves with which they register whereby to provide large free entry or escape ports, as the case may be, for hydraulic fluid with respect to an annular fluid communication groove or channel 45 in the wall of the casing slidably encircling the sleeve 42 at the port slots. The channel 45 communicates by way of a duct bore 47 with the fluid port 20.

Spaced forwardly from the fluid orifice or port slots 43 and 44, is another pair of diametrically opposite fluid orifice or port slots 48 and 49 which are located 90° angularly from the first mentioned slots 43 and 44, respectively. The slots 48 and 49 afford communication between the grooves 38 and 40, respectively, and an encircling fluid groove or channel 50 in the surrounding wall of the casing communicating with the duct bore 51 in the casing leading from the port 19 (Figures 1 and 6).

Spaced further forwardly along the sleeve 42 and just short of the helical twist or diversion portions of the distributor grooves is another annular series of ports, four in number, each of

which is identified by the numeral 52, and which respectively open into the grooves 38, 39, 40 and 41 (Figures 4 and 7). These slots 52 are adapted to register successively with and afford communication between the respective distributor grooves and individual, relatively narrow, radial communication ducts 53 which lead from the respective piston pressure chambers 31 to the closely slidably fitted surrounding bore wall within which the distributor sleeve 42 is rotatable with the shaft 15.

Communication between the several distributor grooves and the forward end pressure chambers 29 for the pistons is effected through radial passages 54 leading therefrom through the bore wall slidably engaging the sleeve adjacent the forward ends of the fluid distribution grooves 38, 39, 40 and 41 and to which (referring to Figures 4 and 9) respective communication orifice slots 55 open through the sleeve 42.

From Figures 7 and 9 it will be observed that the radial communication ducts 53 and 54 are slightly narrower than the land areas of the sleeve 42 intervening between the respective orifice or port slots 52 and 55. Further, it will be observed that the slots 52 and 55 are of a chordal length with respect to the perimeter of the sleeve 42 to communicate simultaneously, in each instance, with two of the radial pressure chamber ducts 53 and 54, respectively. As a result, each of the distributor grooves is, at all times, in communication with the rear pressure chamber 31 of two of the pistons and with the forward pressure chambers 29 of two different ones of the pistons 90° removed in the direction of spiral of the grooves.

Since there are ten of the pistons 18, and four of the distributor grooves, eight of the pistons will be under hydraulic thrust load, four in one direction and four in the opposite direction by alternate pairs uniformly around the piston circuit. This leaves one pair of diametrically opposite pistons in every operating interval now operating or neutral while changing thrust direction as determined by interaction of the piston shoulders 25 with the reciprocation-controlling groove 33. The four intervening land portions between the distributor slots 52 and 55 are so correlated with the reversals of the cam groove 33 and the ten pistons, that the pressure chamber neutralizing progression of the lands is by 144° jump progression in the direction of rotation of the shaft 15, thus overtaking each piston and shutting it off from the hydraulic circuit as it reaches the limit of its stroke in either direction and prepares to reverse its thrust direction. In other words, having reference to Figure 7, where the lands between the slots leading to the grooves 38 and 41 at one side and between the grooves 39 and 40 at the opposite side are in cut-off relation to respective communication ducts 53, rotation of the shaft 36° in either direction will displace such lands and render the land 90° around between the slots leading to grooves 38 and 39 on one side and the land between the slots leading to the grooves 40 and 41 at the opposite side effective for neutralizing cut-off. Simultaneously there is coordinated neutralizing cut-off action by the lands between the distributor slots 55 at the opposite end of the piston series, as shown in Fig. 9.

Operational coordination with respect to the action of the piston cycle controlling groove 33 and the hydraulic fluid distributor system is assured by having the grooved ring 32 keyed in proper angular relation to the sleeve 42. To this end, the distributor sleeve 42 is provided with

a slightly enlarged-diameter intermediate portion 58 (Figures 4 and 8) to which the grooved sleeve 32 is fixedly attached and secured against any possible rotation by means of a key 58a.

In fabricating the shaft 15 and the distributor assembly thereof, the shaft is first turned down at least to provide the bearing collar 35 and the distributor section 37. It is then formed with the distributor grooves 38, 39, 40 and 41, and with the keyway 22 which, it will be observed in Figures 4 and 10, is disposed with its longitudinal center 45° from the adjacent end axes of two of the distributor grooves, herein the grooves 39 and 40. Thereafter the sleeve 42 is press-fitted into enclosing relation onto the intermediate distributor portion 37 of the shaft, with the forward end of the sleeve abutting the rearward shoulder defined by the bearing collar 35. Thorough fluid proofing of the sleeve 42 with respect to all engaged areas of the shaft portion 37 is effected by means such as copper brazing. The shaft and sleeve thus become an integral unit. Preferably after this, the sleeve 42 is turned down to provide the larger diameter control ring receiving portion 58. Then the several orifice slots communicating through the sleeve 42 with the distribution grooves in the shaft are cut as by milling the same, the keyway 22 affording a convenient guide for proper disposal of the several slots. After the assembly is then appropriately further machined and ground, if that is still necessary, depending upon preferred shop practice, the cam groove ring 32 is press fitted onto the sleeve portion 58 and keyed in place, and the completed shaft and distributor assembly is ready to be assembled with the casing 17.

For convenience in fabrication and assembly the casing 17 is preferably made in a plurality of stacked or coaxially assembled sections. These sections will be described substantially in the order in which assembly thereof is adapted to be effected.

The rear end of the casing 17 is in the form of a section 59 which has formed therein at diametrically opposite sides of its rear face and opening rearwardly the hydraulic fluid ports 19 and 20, the latter being preferably appropriately tapped to have hydraulic fluid ducts (not shown) of a fluid circuit threadedly secured therein. An axial rearward opening 60 in the section 59 gives access into the central shaft bore thereof for assembling the bearing assembly 24 which is press-fitted into a rabbet groove 61 in proper position to receive the bearing end pilot terminal 34 of the shaft. The opening 60 is preferably closed by a removable sealing plug 62. The casing section 59 is of a length to encompass the distributor sleeve 42 up to and including the distributor orifice slots 52, and at its forward face has the pressure chambers 31 and the passages 53 formed therein.

In order to isolate the fluid distribution groove 45 from the chamber for the rear bearing 24, an expanding pressure sealing ring 63 is mounted therebetween in a groove 64 in the shaft bore wall of the casing section 59. The distributor grooves 45 and 50 are pressure isolated from one another by a pressure sealing ring assembly 65 in an annular groove 67, while an isolating pressure sealing ring assembly 68 is disposed in a groove 69 intervening between the distributor groove 50 and the pressure chamber ducts 53.

Next in order in the casing assembly is an intermediate section 70 which abuts the forward

75

end of the section 59 and has the piston bearing bores 30 and the piston shoulder clearance bores 28 formed therein, as well as an annular chamber 71 (Figures 4 and 8) affording clearance for the cam groove ring 32 and intersecting the radially inner sides of the piston shoulder clearance bores 28. A pressure sealing ring 72 seated in an annular groove 73 seals the pressure chamber ducts 53 from the chamber 71.

Abutting the front end of the section 70 is a piston bearing ring section 74, the principal function of which is to provide the piston bearing bores 27. Forwardly of this the assembly includes a casing ring section 75 which in the rear face abutting the ring section 74 has the compression chambers 29 and the ducts 54 formed therein. Escape of hydraulic fluid pressure from the ducts 54 longitudinally of the shaft is prevented by a sealing ring 77 in an internal annular groove 78 in the ring section 74 and a sealing ring 79 in an internal annular groove 83 in the ring section 75.

At its forward end the casing ring section 75 has an internal rabbet groove 81 within which the outer race of the bearing assembly 23 is seated in fixed longitudinal relation to the casing 17. Since the inner race of the bearing assembly is held fast against a shoulder 82 at the forward end of the sleeve 42, by means of a nut 83 carried by a forward, threaded portion 84 on the shaft, it will be apparent that the shaft is supported in longitudinal thrust relationship by the front bearing assembly 23. A longitudinal keyway 85 is provided for reception of the retaining leg of a conventional bearing lock washer 86 associated with the nut 83.

A forward end cap section 86 completes the housing sections and is formed with an internal bearing rabbet groove 87 complementary to the groove 81 for reception and holding of the outer race of the bearing assembly 23. A groove 88 forwardly of the bearing groove 87 affords a chamber for clearing the nut 83. The forward portion of the cap section 86 has a slideable bearing bore 89 for passage of the shaft 15, and an expansion type sealing ring 90 is disposed in an internal groove 91 encircling the shaft for preventing leakage of hydraulic fluid past the shaft out of the housing from the front bearing chamber.

Since the intermediate ring sections 70 and 74 of the housing have the bearing bores 30 and 27, respectively, for the pistons 18, it is highly essential that these sections be in accurate angular registration, and for this purpose stakes 92 (Figure 8) may be provided at appropriate intervals. Use of these aligning stakes permits coaxial boring and lapping of the aligned bearing bores 27 and 30.

All of the sections of the casing are held together in tight assembly by means such as a plurality of tie bolts 93 (Figures 3, 4 and 7) which are accessible from the front of the unit and have the heads thereof countersunk within counterbores 94 in the cap section 85.

For attachment of the front end of the unit to a supporting structure, the cap section 85 may be provided with an annular radial flange 95 provided with an annular series of spaced axially extending bores 97 for receiving attachment bolts or the like. The rear end of the cap section 85 and the adjacent portion of the housing ring section 75 are provided with external insets 98 for clearing the attachment bolt heads or nuts. Of course, if preferred, any other means may be pro-

vided on the unit for attaching it to supporting structure, such as a foot or base or the like, as is common practice in mounting motors or pumps.

In the operation of the unit, where it is used as a motor, hydraulic fluid under pressure is introduced either through the port 19 or the port 20, the alternate port then serving as an outlet or exhaust port. Instantaneously upon introduction of the pressure fluid through the port 19, for example, it enters the distributor grooves 38 and 40 which provide passage therefor to the operating zone involving the pistons 18. At the same time the remaining grooves 39 and 41 serve as return passages for the spent hydraulic fluid. Where the pressure fluid is introduced by way of the port 20 it will, of course, enter and travel by way of the grooves 39 and 41 to the pistons and return by way of the grooves 38 and 40. The respective orifice slots 52 and 53 leading from the grooves valve the pressure fluid to the respective opposite ends of the pistons 18 to be actuated. By reason of the 90° spiraling of the grooves, the piston ends opposite to the thrust are always in communication with the low pressure or return grooves leading to the exhaust port.

Inasmuch as each of the slots 52 and 55 always, in any angular position thereof, communicates with two pressure chamber communication ducts, there is a continuous and progressive overlapping of piston thrust around the entire circuit, thus assuring smooth, powerful, uniform, vibrationless power transmission to the cam ring 32 and thus the shaft 15, without any possibility of dwell or stalling at any point in the circuit. The motor is therefore capable of instantaneous starting and stopping. Furthermore, it will be readily apparent that the motor is instantly reversible, within the practical limits permitted or required in the associated driven apparatus.

When in use as a pump, the unit is capable of creating hydraulic pressures on the order of those utilized when the unit is operated as a motor. For this purpose, rotary power input through suitable connection with the forward end portion 21 of the shaft 15 causes the pistons 18 to be driven as pumping pistons, and the fluid distributor system operates in reverse from its operation where the device is used as a motor. That is, the hydraulic fluid is drawn in through one of the ports 19, 20 and is impelled under pressure from the other of such ports, depending upon the direction in which the shaft 15 is driven. Similarly as when the device is used as a motor, reversal of direction may be accomplished as nearly as practicable instantaneously and without any alteration in the mechanism or any adjustment required. In fact, the use of the unit either as a motor or as a pump is merely a matter of choice or expediency and is not dependent upon any adjustment or alteration in the mechanism. In both instances maximum efficiency, without any dwells, surging, lag or fluctuations in power output when the device functions as a motor, or in hydraulic fluid pressure when the device is utilized as a pump, will occur at any point in or between any cycle of operation as determined by a revolution of the shaft 15.

It may also be noted that throughout the unit the fluid distribution system provides passages and ports or orifices which are large in cross sectional area as compared with the respective piston areas. There is therefore a minimum of power loss from frictional resistance, the unit is cool running and of high efficiency.

Any possibility of pressure binding and at-

tendant drag and frictional losses within the unit due to inevitable escape or leak-by of high pressure fluid into non-pressure working areas of the unit, is avoided by the provision of a thorough scavenging system. This system is so arranged that complete self-lubrication of the working parts in the unit is accomplished. Also cooling of those parts which may be subject to frictional heating due to mechanical parts interaction during high speed, high pressure operation is effectively performed. Thus, by the present invention leak-by fluid which might otherwise create internal resistances and resulting power loss and frictional heating of the unit, is actually put to good use and is maintained at low, non-obstructing pressure, or even at negative pressure.

At the heart of the scavenging system are means for relieving the working area within the unit where the greatest potential leak-by occurs from the very nature of the operating mechanism, namely the area within which the pistons 48 operate. To this end, the piston shoulder clearance bores 28 and the connecting cam sleeve chamber 71, treated as a leak-by reservoir chamber entity, as for all practical purposes they are, have relief communication with the low pressure or suction side of the hydraulic system of the unit, irrespective of the direction of motivation prevailing at any given time in the unit. For this there is relief duct 100 communicating with the hydraulic fluid duct or passage 51 to the port 19, and a relief duct 101 communicating with the hydraulic fluid duct or passage 47 to the port 20. The relief ducts 100 and 101 are formed in the housing section 59. At the forward face of the housing section 59 the ducts 100 and 101 have communication with respective slightly larger diameter relief ducts 102 and 103, respectively, formed in the housing section 70 and opening into the piston clearance chamber area. A normally closed check valve 104 in each of the relief ducts 102 and 103 is biased by means such as a compression spring 105 to remain closed and to check high pressure flow of hydraulic fluid toward the piston clearance chamber area, but to respond to suction from the active hydraulic fluid circulation system of the unit, or a combination of such suction and mild internal pressure created by the leak-by fluid in the piston clearance chamber, for bleeding off excess leak-by fluid.

It is preferred to maintain a reasonable supply of leak-by fluid in the piston clearance chamber for lubricating and cooling the pistons 48 and the cam ring 32 in view of the relatively close bearing relation of the shoulder portions 25 of the pistons within the cam groove 33, even though by the construction of the bearing surfaces and the rotational running of the shoulders 25 in the groove during operation frictional resistance is minimized. Lubrication is effected due to the fact that the shoulders 25 and the cam groove 33 are running in a bath of the hydraulic fluid, which is customarily an appropriate oil.

In addition to cooling afforded by the fluid at the outer face of the cam ring 32, internal cooling is provided for through the medium of a communication bore 107 which together with a bore 108 extends through the ring 32 and communicating with an internal annular groove 109 in the internal wall of the ring. The groove 109 cooperates with a complementary groove 110 in the supporting portion 58 of the distributor tube or sleeve to provide a coolant circulation channel (Figures 4, 13 and 14). By preference, the bores

107 and 108 are formed at the opposite side of the ring 32 from the internal keyway therein and have the mouths thereof in proximity at the periphery of the ring. The bore 107 is preferably formed at a slight angle to the radius of the ring 32, tilted away from the mouth of the bore 108 approximately 10° from the sleeve radius. On the other hand, the bore 108 is preferably formed substantially tangential to the internal circulation groove 109 and tilting toward the groove 107. This arrangement promotes coolant circulation through the groove 107 in the rotation of the cam groove ring. It facilitates entry of means such as a keying wire 108a (Figs. 4, 8 and 14) into the communicating portion of the passage 109-110 of the assembly to lock the ring 32 positively against axial movement relative to the sleeve 42.

Provision is made for draining off leak-by fluid from other parts of the operating mechanism to the piston clearance chamber, or, on the other hand, delivery of the fluid to such parts for lubricating purposes where an inadequate supply of hydraulic fluid leaks by to such areas. To this end, the shaft 15 is formed in the distributor area 37 thereof with longitudinal grooves 111 (Figures 10, 11 and 12) which are disposed in the land areas between the fluid distribution grooves 38 to 41, inclusive. The rear ends of the relief 25 grooves 111 open into the rear bearing chamber. The front ends of the grooves 111 extend for a short distance into the bearing supporting area 35 of the shaft and have communication by way of end notch ports 42 in the distributor sleeve 32 with the front bearing chamber.

Communication between the grooves 111 and the piston clearance chamber at the operative center of the unit is effected through radial bores 113 (Figures 4 and 8) through the sleeve 42 at 30 one side of the cam sleeve supporting area 58. In this fashion, leak-by fluid which may tend to accumulate in the bearing chambers will be drawn off through the longitudinal shaft grooves 111 to the piston clearance chamber. On the 35 other hand an equalization of lubricating fluid between the bearing chambers and the central piston clearance chamber is attained. Furthermore, this lubricating and relief system is independent of the direction of hydraulic flow in 40 the operating circuit since the relief system is at all times in controlled communication with the suction side of the system and the check valves 104 prevent entrance of pressure fluid into the scavenging system.

55 Fluid circulation between at least one of the relief grooves 111 and the coolant circulation portion of the annular internal keying fluid channel 109-110 may be provided for by a radial bore 114 through the sleeve portion 58 between the 60 bottom of the groove 110 and the selected groove 111.

It will, of course, be understood that various details of construction may be varied through a wide range without departing from the principles of this invention and it is, therefore, not the purpose to limit the patent granted hereon otherwise than necessitated by the scope of the appended claims.

I claim as my invention:

70 1. In a combination hydraulic motor or pump unit, a casing, a shaft rotatable in the casing, longitudinal fluid distribution grooves on said shaft within the casing, a distributor sleeve 75 extensively encompassing the grooved portion of the shaft and closing the grooves to convert them

into closed ducts, said sleeve having hydraulic fluid distribution orifices therein communicating with the grooves, the casing having means for communicating with a hydraulic fluid supply exteriorly of the casing and cooperating with the distributor grooves and orifices to provide a fluid circuit within the unit, a plurality of pistons, and thrust transmission means carried by said sleeve and operatively coacting with the pistons, said orifices having operative communication with the pistons, whereby when the unit is operating as a motor high pressure hydraulic fluid is supplied through said grooves and orifices for actuating the pistons and thereby driving the shaft through said thrust transmission means and when the unit is operating as a pump rotation of the shaft effects operation of the pistons through said thrust transmission means for pumping the hydraulic fluid through said orifices and grooves.

2. A unit as defined in claim 1 wherein the thrust transmission means on the sleeve operatively coacting with the pistons comprises a helically grooved ring mounted fixedly on the distributor sleeve, and the pistons have interengaging shoulder means within the helical groove.

3. A unit as defined in claim 2 wherein the walls of the helical groove and the shoulder means on the pistons are formed as nearly as practicable complementary so as to interfit closely on both sides of the groove.

4. A unit as defined in claim 2 wherein the groove comprises multi-helical portions effective to control relative movement of the pistons through a plurality of stroke cycles in each revolution of the shaft.

5. In combination in a hydraulic motor or pump unit of the character described, a casing having means for communicating with a hydraulic fluid circuit, a shaft rotatably mounted in the casing, a plurality of longitudinal individual peripheral fluid distribution grooves in the intermediate portion of the shaft, said grooves being in straight coextensive parallelism for a portion of their length and thence extending in coextensive spiral direction about the shaft, a sleeve about the shaft enclosing said grooves and isolating the grooves one from the other, a plurality of pistons disposed about the shaft within the casing, an operating connection between the shaft and the pistons, fluid supply and exhaust ports through said sleeve communicating with the hydraulic circuit communication means, and annular series of ports through said sleeve communicating with the grooves for hydraulic fluid distribution with respect to the pistons, one of said series of ports and said source communication ports being associated with the straight portions of the grooves and a remaining series of distribution ports being associated with the spiral portions of the grooves.

6. A unit according to claim 5 wherein the pistons are double acting and each having opposite end pressure heads, and the respective series of distribution ports in the distributor sleeve on the shaft communicate with the respective opposite ends of the pistons.

7. In a unit of the character described, a rotary shaft, a longitudinally extending annularly spaced series of fluid distribution grooves on an intermediate portion of the periphery of the shaft, and a sleeve enclosing the grooved portion of the shaft in fluid-tight relation and thereby closing off the grooves from one another, said sleeve having a plurality of annular longitudi-

nally spaced series of fluid distribution orifices opening therethrough in communication with the grooves.

8. A structure according to claim 7 wherein said sleeve carries, intermediate a pair of series of distribution orifices, a cam ring for operative association with a set of shouldered piston elements.

9. A structure according to claim 7 wherein the shaft has grooves separate from the fluid distribution grooves and parallel thereto but extending beyond the ends thereof and serving as leak-by passages.

10. In a unit of the character described, a casing, a shaft rotatably mounted in the casing, a concentric series of pistons having opposite pressure ends and being operatively disposed within the casing about the shaft and having intermediate rib-like, radial, tapered annular shoulders, means defining pressure chambers at the respective opposite ends of the pistons, longitudinally spaced annular hydraulic fluid communication areas on the casing wall communicating with respective portions of the shaft, the shaft having longitudinal hydraulic fluid distribution channel grooves in the periphery thereof, an encircling sleeve on the shaft closing said channel grooves from each other, ports through said sleeve communicating with respective ones of said channel grooves at said respective areas of hydraulic fluid communication, and respective series of ports through said sleeve communicating with the channel grooves and with said pressure chambers.

11. A unit as defined in claim 10 wherein the casing has a chamber affording clearance for reciprocal movement of the piston shoulders, and passages having pressure controlling check valves therein lead from said chamber to the respective hydraulic fluid communication areas.

12. A unit as defined in claim 11 wherein the shaft has additional leak-by grooves therein opening beyond the ends of said sleeve and having communication through said sleeve with said chamber.

13. A unit according to claim 12 including bearings supporting the shaft beyond the opposite ends of said sleeve, the casing having chambers therein accommodating the bearings, and the leak-by grooves communicating with the bearing chambers.

14. In combination in a unit of the character described, a casing, a shaft rotatable in the casing, a plurality of reciprocable pistons disposed in concentric series about the shaft within the casing, a chamber surrounding the shaft within the casing in the region of the pistons, annular follower shoulders on the pistons, and a cam ring encircling the shaft and secured fast thereto, said cam ring and the follower shoulders being operatively associated, said chamber being normally adapted to contain hydraulic fluid in lubricating relation to the cam ring and the piston shoulders, said cam ring having an internal coolant flow channel and passage therethrough to said channel for circulation of the hydraulic fluid in cooling relation internally of the ring.

15. In a cam ring of the character described adapted to be applied to a cylindrical support equipped with a longitudinal keyway and a circumferential keyway, the ring having a cylindrical bore to fit about the cylindrical support, said bore having longitudinal and circumferential keyways matching and complementary to

the like keyways on the support, and a bore extending through the ring and running tangentially into said annular groove keyway in the bore spaced from the longitudinal keyway of the bore and adapted to receive keying means therethrough to hold the ring against longitudinal movement relative to the support.

16. In combination in an overlapping thrust multi-piston motor or pump unit, a casing, a rotary shaft bearing in said casing, a plurality of pistons each having opposite pressure thrust ends, means within the casing about the shaft providing bearing bores for the opposite end portions of the pistons and disposed on parallel axes about the shaft, said casing providing a chamber about the shaft and the intermediate portions of the pistons, means on the pistons and on the shaft cooperative within said chamber and providing for thrust transmission between the shaft and the pistons, the casing providing means therein at the opposite ends of the pistons defining pressure chambers, means providing a reversible hydraulic circuit within said casing and communicating with said pressure chambers, said hydraulic circuit means including a pair of hydraulic passages communicating with openings to the exterior of the casing, and means defining a pair of passages within said casing communicating between respectively said externally communicating passages and said chamber and each including therein a check valve to prevent pressure fluid flow into said chamber but responsive to suction in the respective externally communicating passages for relieving pressure in said chamber.

17. In a unit of the character described, a rotary shaft, a series of longitudinally extending annularly spaced fluid distribution grooves on an intermediate portion of the periphery of the shaft and having the ends thereof terminating short of the respective opposite ends of the shaft, said shaft periphery intermediate said grooves having longitudinally extending leak-by passage grooves, and a sleeve enclosing the grooved portion of the shaft and entirely closing said fluid distribution grooves, said leak-by passage grooves extending beyond the opposite ends of the sleeve, said sleeve having fluid distribution orifices opening therethrough in communication with the respective opposite ends of said fluid distribution grooves.

18. For use in a multi-piston motor or pump, a rotary shaft, said shaft having a series of longitudinally extending annularly spaced fluid distribution grooves therein extending short of the respective opposite ends of the shaft, said grooves being throughout their length parallel to one another and each having a portion thereof extending parallel to the axis of the shaft and parallel to all of the remaining grooves and a portion thereof extending spirally into offset relation to the straight portion of the groove, a sleeve enclosing the grooved portion of the shaft and closing the grooves off from one another, said sleeve having individual orifices opening therethrough and communicating with the offset portions of the grooves.
19. In combination in a hydraulic motor or pump unit, a casing including means for accommodating a hydraulic fluid circuit, a shaft rotatable in the casing, a series of reciprocable pistons operatively mounted on parallel axes about said shaft, means providing cylinders for said pistons and cylinder head spaces in communication with said hydraulic fluid circuit accommodating means, thrust transmission means between said shaft and said pistons, said casing defining a chamber affording operative clearance for the thrust transmission means, said chamber serving also as a leak-by reservoir for hydraulic fluid escaping past the pistons into the chamber, and means defining fluid relief passageway leading from the chamber for communication with the suction side of the hydraulic fluid circuit.
